UNITED STATES PATENT OFFICE.

JOHN H. B. BRYAN, OF BUFFALO, NEW YORK, ASSIGNOR TO NILES-BEMENT-POND COMPANY, OF JERSEY CITY, NEW JERSEY.

DRIVING MECHANISM FOR PLANER-PLATENS.

No. 918,652.

Specification of Letters Patent.

Patented April 20, 1909.

Application filed June 18, 1906. Serial No. 322,184.

To all whom it may concern:

Be it known that I, JOHN H. B. BRYAN, a citizen of the United States, residing at Buffalo, in the county of Erie and State of New York, have invented a new and useful Improvement in Driving Mechanism for Planer-Platens, of which the following is a specification.

This invention relates to a driving mechanism for the platens of planers and more particularly to a driving mechanism embodying a pneumatically operated clutch mechanism whereby the movement of the planer platen is reversed at the end of its stroke in both directions. The pneumatic clutch mechanisms heretofore used for this purpose were faulty because they permitted reversing of the driving mechanism to be effected under the full pressure of the air which caused breakage of the driving mechanism when the air was used under high pressure or permitted slipping of the clutches and consequently produced uncertain movement of the platen when the air was used under comparatively low pressure.

One of the objects of this invention is to provide pneumatic means for operating the clutches of a planer platen driving mechanism which permits air under high pressure to be used for moving the platen reliably during the main part of its stroke in both directions but reduces the effectiveness of the air pressure while reversing the movement of the platen and thus avoids the objectionable results mentioned above.

My invention has the further objects to improve the driving mechanism of the platen in several details.

In the accompanying drawings consisting of 2 sheets: Figure 1 is a side elevation of a planer having its platen operated by my improved driving mechanism. Fig. 2 is a top plan view thereof partly in section. Fig. 3 is a longitudinal section, on an enlarged scale, of the air reversing valve. Fig. 4 is a similar view of one of the branch air pipes together with its check valve and by-pass. Fig. 5 is a fragmentary longitudinal section, on an enlarged scale, showing the pneumatic clutches and the parts operatively connected therewith. Fig. 6 is a similar view, on an enlarged scale, showing part of the air connections of the pneumatic clutches. Fig. 7 is a transverse section in line 7—7, Fig. 6. Fig. 8 is a horizontal section of one of the oil

catchers, separators or traps arranged in the branch air pipes. Fig. 9 is a vertical cross section of the same in line 9—9, Fig. 8.

Similar letters of reference indicate corresponding parts throughout the several views.

The planer shown in the drawings for illustrating the application of my improved platen driving mechanism consists essentially of a bed A, a horizontally reciprocating platen or table B guided on the bed and adapted to carry the article to be planed, a tool holder C supported above the platen by means of standards c and carrying the tool d which operates upon the article to be planed, a main gear or bull wheel E mounted on the bed and meshing with a gear rack e on the underside of the platen and a driving shaft F journaled transversely on the bed and provided with a gear pinion f which meshes with the bull wheel.

The platen may be driven by any suitable motor but preferably by an electric motor G, as shown in the drawings. The gearing and pneumatic reversing clutches whereby the movement of this motor is transmitted to the driving shaft F of the platen may be variously constructed, that shown in the drawings, as an example, being constructed as follows: H represents a clutch shaft connected at one end by intermeshing beveled gear wheels h with the adjacent end of the platen driving shaft F. I, I' two cylindrical clutch barrels mounted loosely side by side on the clutch shaft and having their open inner ends facing each other. J represents a counter shaft arranged parallel to the clutch shaft and provided with a gear wheel j which meshes with a gear wheel j' secured to the clutch barrel I. K represents an intermediate gear wheel meshing on opposite sides with the gear wheel j on the counter shaft and a gear pinion k' on the motor shaft, as shown in Fig. 5. L represents an intermediate shaft arranged parallel with the counter and clutch shafts and provided at one end with a pinion l which meshes with a gear wheel l' secured to the other clutch barrel I' while its opposite end is provided with a gear wheel m which meshes with the gear wheel M on the corresponding end of the countershaft. The motion of the counter-shaft which rotates continuously in the same direction is transmitted by the gears j, j' to the clutch barrel I so that the same is turned

in one direction while the gear wheels M, m, 110

l, l' operate to turn the other clutch barrel *I'* in the opposite direction. During the normal operation of the planer the clutch shaft is connected alternately with the clutch barrels, whereby the clutch shaft is rotated alternately in opposite directions and the platen is reciprocated. *N* represents a clutch sleeve secured to the central part of the clutch shaft so as to practically form a part thereof and projecting with its ends into the clutch barrels. *o* represents two sets of driving clutch rings or disks arranged in the clutch barrels and connected therewith by splines so as to be capable of axial movement relatively thereto but compelled to rotate therewith. *o'* represents two sets of driven clutch disks or rings mounted on the ends of the clutch sleeve and connected therewith by splines which compel the driven disk to turn with the clutch sleeve and shaft but permit them to move axially relatively thereto. Each set of driven disks alternate with the driving disks of one set of disks so that upon pressing together lengthwise the several disks of two co-operating sets of driving and driven disks the clutch barrel carrying the respective set of driving disks will be coupled with the clutch shaft. *P* represents a shifting cylinder arranged between the outermost clutch disks of the two clutches and having the heads *p, p'* at its opposite ends mounted on the central part of the clutch sleeve so as to be capable of sliding lengthwise thereon but having an air tight joint between the same and the clutch sleeve. *p'* represents a piston or abutment arranged on the central part of the clutch sleeve and bearing with its periphery against the bore of the shifting cylinder. Upon admitting compressed air into the shifting cylinder between its head *p* and the piston *p'* the shifting cylinder will be moved lengthwise toward the clutch barrel *I* and cause the several clutch disks within the same to be pressed against each other, thereby forming a frictional coupling between said clutch barrel and the clutch shaft and causing the platen to be moved in one direction. Upon admitting air into the shifting cylinder between its head *p'* and the piston *p* the shifting cylinder will be moved lengthwise in the opposite direction and cause the several disks within the clutch barrel *I'* to be pressed together, thereby frictionally coupling the clutch shaft with the clutch barrel *I'* and causing the platen to be moved in the opposite direction.

The means whereby the air is alternately admitted to and exhausted from opposite ends of the shifting cylinder are constructed as follows: *Q* represents a stationary air box mounted on a reduced extension *H'* at the front end of the clutch shaft and secured by bolts or otherwise to the adjacent bearing of the clutch shaft so that this shaft turns in

said box. In the central part of the bore of this air box the same is provided with an annular air chamber or enlargement *q* which surrounds the extension of the clutch shaft and is connected with an air branch pipe or conduit *R* which conducts pressed air to and from this chamber. The central part of the clutch shaft extension is bored out to form an air chamber *S* which communicates by one or more radial passages *s* in the shaft extension with the air chamber *q*. From the chamber *S* to a point adjacent to the piston *p'* the clutch shaft is bored out to form an axial conduit or passage *s'* which is connected near its inner end with the space in the shifting cylinder between its head *p* and the piston by means of a lateral passage *s''* formed partly in the clutch shaft and the surrounding clutch sleeve. Air tight joints are produced between the shaft extension *H'* and the bore of the air box on opposite sides of its air chamber by means of two packing devices each of which preferably consists of an *L* shaped packing ring of leather, felt or similar material having an inner cylindrical portion *t* which embraces the adjacent peripheral portion of the shaft extension, a radial flange *t'* projecting outwardly from the outer edge of the cylindrical part *t* and bearing with its inner side against a shoulder *t''* on the air box, a clamping ring *t'''* bearing against the outer side of said radial flange, bolts *t''* connecting said clamping ring and air box and passing through said radial flange and a split retaining ring *t'''* arranged in an enlargement of the bore of the air box and bearing inwardly against the outer side of the cylindrical portion of the packing ring, as shown in Figs. 6 and 7. The air enters between the bore of the air box and the outer side of the cylindrical flanges *t* of the packing rings and presses these flanges against the periphery of the shaft extension *H'*, thereby effectively preventing leakage of air at these points. *U* represents a central air pipe or conduit arranged axially within the conduit *s'* and chamber *S* of the clutch shaft and its extension and projecting at its outer end into an opening *u* formed in the outer wall of the air chamber of the shaft extension. The outer diameter of this central pipe is smaller than the bore of the conduit *s'* so as to leave an annular space around the central pipe for the passage of air. At its inner end the central pipe *U* is tapered and bears against a correspondingly shaped shoulder formed by reducing the inner end of the bore or conduit *s'*. At its outer end the central pipe communicates with a tubular plug *u'* which is screwed into the outer end of the shaft extension. The outer end of said central pipe is tapered and bears against a correspondingly shaped shoulder on the inner end of the plug *u'* to form an air tight joint between

these parts. Communication is established between the inner end of the central pipe U and the shifting cylinder between its head p^1 and the piston by a passage u^2 formed partly in the clutch shaft and the clutch sleeve, as shown in Fig. 5. Air is conducted to and from the central pipe U by means of a branch air pipe w which is connected with the central pipe so that the latter is free to rotate together with the clutch shaft without disturbing the air connection between the central pipe and the branch pipe w . The preferred form of joint for this purpose between these parts consists in arranging the end portion of the branch air pipe w axially within the outer part of the plug u^1 so that its passageway or bore communicates with the bore of the opening or passage u^2 leading to the central pipe and producing an air tight joint between this end of the pipe and the plug by means of a head w^1 arranged at the inner end of the branch pipe w and bearing on its inner side against a packing u^3 resting against an internal shoulder on the plug, a plurality of packing rings w^2 surrounding the branch pipe w within the bore of the plug and bearing against the outer side of its head, a follower sleeve w^3 surrounding the branch pipe within the bore of the plug and bearing against the outermost packing ring, and a gland w^4 having a screw connection with the outer end of the plug and bearing against the outer end of the follower, as shown in Fig. 6.

The valve mechanism whereby the compressed air is alternately admitted to the conduits or branch pipes R, w leading to opposite ends of the shifting cylinder is best shown in Figs. 1, 2, 3 and 4 and is constructed as follows: X represents an air chest which is connected on one side with a compressed air supply pipe x while another side thereof is provided centrally with an exhaust port x^1 leading to the atmosphere and on opposite sides of said exhaust port with two distributing ports x^2, x^3 which communicate with the branch pipes w, R respectively. x^4 represents a slide valve arranged in the air chest and provided on its under side with a cavity x^5 whereby upon sliding this valve to the end of its movement in one direction one of the distributing ports will be uncovered and placed in communication with the air supply pipe for delivering compressed air to one end of the shifting cylinder while the other distributing port is cut off from the air supply pipe and connected by the cavity x^5 with the exhaust port to permit the spent air to escape from the opposite end of the shifting cylinder. The slide valve is reciprocated for alternately connecting the distributing ports with the air supply and the exhaust by means of a valve or slide rod x^6 connecting with the slide valve and passing through a stuffing box in the air chest, a rock shaft x^7 mounted

on the planer bed and having a depending arm x^8 which is connected by a link x^9 with the valve rod and two tappets x^{10}, x^{11} projecting upwardly from said rock shaft and adapted to be engaged alternately by shoulders or trip blocks x^{12}, x^{13} on the platen. By this means the rock shaft x^7 is turned alternately in opposite directions at opposite ends of the reciprocating movement of the platen and thus causes the air connections between the supply pipe and the shifting cylinder to be reversed intermittently for producing the reciprocating movement of the platen. It has been found in practice that if the spent or dead air is permitted to escape freely from the inoperative end of the shifting cylinder while compressed or live air is being admitted into the opposite end of this cylinder the release of one clutch and the tightening of the other is effected too suddenly causing frequent stripping of the gear teeth and breakage of other parts of the transmitting gearing. This is particularly liable to happen when air under high pressure is used for moving heavy loads. It has been attempted to overcome this difficulty by reducing the air pressure to such a point that the sudden reversal of the clutches will not injuriously affect the transmitting mechanism but this is objectionable inasmuch as air when supplied at low pressure will not couple the clutch firmly but permit slippage of the same particularly during the cutting stroke at which time the movement of the platen is uncertain and irregular and liable to be stopped and also causes chattering of the tool, thereby producing a non-uniform cut.

In order to permit of utilizing the air under high pressure for positively and reliably moving the platen and the article mounted thereon and at the same time prevent sudden reversal of the clutch mechanism, means are provided for permitting the compressed or live air to flow forward freely and unrestricted through the branch pipes for coupling the gripping members of the respective clutches and to restrict or retard the return flow or exhaust of the spent or dead air through said branch pipe so as to operate like a dash pot or air cushion which resists sudden movement of the shifting cylinder in the operative direction under the force of the live air. Various means may be employed for producing this effect the means shown in the drawings serving as an example and being constructed as follows: Y represents the casings of check valves arranged in the branch air pipes and each provided with a valve y which is moved from its seat while the pressure of the air in moving forwardly through the branch pipe from the supply to the respective end of the shifting cylinder but is closed either by the movement of the returning spent air, by gravity or by means of a spring. Each of the branch pipes is pro-

vided with a by-pass or pipe y^1 which is connected at its opposite ends with the respective branch pipe on opposite sides of its check valve, as shown in Figs. 1, 2 and 4. 5 Each of the by-passes or pipes contains a valve y^2 whereby the capacity of the by-pass may be restricted more or less as may be necessary. The compressed live air opens the check valve wide and flows freely through 10 the branch pipe on its way to one end of the shifting cylinder for coupling one clutch but during the return movement of this air when spent the check valve closes so that its only 15 exit is through the restricted by-pass which causes the escape of the spent air to be retarded. The uncoupling of one clutch and the coupling of the other is thus effected gradually causing the movement of the platen to be reversed without any injurious 20 shock but when the reversal has been completed the full pressure of the air is available for firmly coupling the operative clutch and causes the platen to be moved forward positively and uniformly during the cutting 25 operation as well as during the return or idle stroke of these parts. For the purpose of reducing the force of the compressed air as it may be necessary to suit the particular work in hand a reducing valve X^1 of any suitable 30 construction is arranged in the main supply pipe. A pressure equalization tank X^2 is also preferably arranged in the main air pipe between the reducing valve and the air chest of the reversible valve. This tank stores a 35 quantity of the compressed air at the reduced pressure and supplies the same as needed by the pneumatic clutches, thereby preventing wire-drawing of the air and preventing fluctuation in the air pressure and 40 consequently causing the clutches to operate uniformly.

In order to prevent the oil which reaches the branch air pipes from the lubricated parts from being blown out through the exhaust and wasted each of the branch pipes is provided with an oil catcher, separator or trap which is constructed as follows: Z represents a separating chamber which is arranged substantially horizontal in the direction of 45 its length and provided in its bottom with a draw-off valve or pet cock z . Within this chamber are arranged two nipples or nozzles z^1, z^2 which are connected with the sections of the branch pipe on opposite sides of the separator and which extend horizontally in opposite directions through opposite heads of the chamber and terminate each with its open 55 inner end short of the head through which the other nozzle passes, as shown in Fig. 8. 60 By this means the air leaving the end of one nozzle and passing through the chamber into the end of the other nozzle is compelled to make a sharp turn, whereby any particles of oil and dirt contained in the same are permitted to separate therefrom by gravity and 65

drop into the bottom of the chamber. The oil accumulating in the bottom of the chamber may be drawn off from time to time by opening the valve z . By thus separating the oil from the air as the same passes through 70 the branch pipes the main or reversing valve and other parts cannot become gummed by this oil and it also prevents any grit and dirt which is carried away from the lubricated surfaces by the oil from reaching the reversing 75 valve and other parts and wearing the same rapidly.

I claim as my invention:

1. A driving mechanism for planer platens comprising two pneumatic clutches which are constructed to move the platen in opposite directions, a main air supply pipe, two branch pipes or conduits connecting with said clutches, a reversing valve for connecting each branch pipe or conduit either with 80 the main air supply pipe or with an exhaust, and means constructed to permit the air to flow freely forward through said branch pipes or conduits but retard the backward flow of the air through the latter, substantially as set forth.

2. A driving mechanism for planer platens comprising two pneumatic clutches which are constructed to move the platen in opposite directions, a main air or supply pipe, two 95 branch pipes or conduits connecting with said clutches, a reversing valve for connecting each branch pipe or conduit either with the main air supply pipe or with an exhaust, and means constructed to permit the air to flow freely forward through said branch pipes or conduits but retard the backward flow of the air through the same, consisting of a forwardly opening check valve arranged in each branch pipe and a restricted by-pass 100 connected with said branch pipe on opposite sides of its check valve, substantially as set forth.

3. A driving mechanism for planer platens comprising two pneumatic clutches which are constructed to move the platen in opposite directions, a main air supply pipe, two branch pipes or conduits connecting with said clutches, a reversing valve for connecting each branch pipe or conduit either with 110 the main air supply pipe or with an exhaust, and means constructed to permit the air to flow freely forward through said branch pipes or conduits but retard the backward flow of the air through the same consisting of a forwardly opening check valve arranged in each branch pipe, a by-pass connected at opposite ends with said branch pipe on opposite sides of its check valve, and a regulating valve arranged in each by-pass, substantially 115 as set forth.

4. A driving mechanism for planer platens comprising two pneumatic clutches constructed to move the platen in opposite directions, two air pipes each of which carries 120

the air to and from one of said clutches, and an oil separator arranged in each of said pipes, substantially as set forth.

5. A driving mechanism for planer platens comprising two pneumatic clutches constructed to move the platen in opposite directions, two air pipes each of which carries the air to and from one of said clutches, and an oil separator arranged in each of said 10 pipes, and consisting of a chamber, and two nozzles connected with sections of the air pipe and extending horizontally in opposite directions through the ends of the chambers and each nozzle terminating at its open inner 15 end short of that end of the chamber through which the other nozzle passes, substantially as set forth.

6. A driving mechanism for planer platens

comprising two pneumatic clutches constructed to move the platen in opposite directions, two branch air pipes each of which carries the air to and from one of said clutches, a main air supply pipe, a reversing valve for connecting each of said branch pipes either with the main supply pipe or 25 with an exhaust, a pressure reducing valve arranged in the main pipe, and a pressure equalizing tank arranged in the main pipe between the reducing valve and the reversing valve, substantially as set forth. 30
